COMBINED PORTABLE VIEWER AND ILLUMINABLE UNIT FOR INSPECTING AIR FILTER CARTRIDGES

Donald L. Paster, Riverside, R. I., assignor to Fram Corporation, Providence, R. I., a corporation of Rhode Island

Application May 1, 1958, Serial No. 50,699

Term of patent 7 years

(Cl. D57—1)

FIG. 3

F I G. 4

Fig. 1 is a perspective view of a combined portable viewer and illuminable unit for inspecting air filter cartridges;

Fig. 2 is a side elevational view thereof;

Fig. 3 is a front elevational view thereof; and

Fig. 4 is a view similar to Fig. 1 but on a larger scale.

I claim:

The ornamental design for a combined portable viewer and illuminable unit for inspecting air filter cartridges, substantially as shown.
